Primary Examiner — Mary Ann Calabrese*Assistant Examiner* — Catherine Ho(74) *Attorney, Agent, or Firm* — Kane Kessler, P.C.; Paul E. Szabo(57) **CLAIM**

We claim the ornamental design for a sign, as shown and described.

DESCRIPTION

FIG. 1 is a perspective view of a sign, showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a cross sectional view taken along the lines 8-8 of FIG. 6.

The broken line portion of the figure drawings is included to show environment that forms no part of the claimed design.
